PIN-UP SPECTACLE CASE OR SIMILAR ARTICLE

Donald D. Dixon, Fort Morgan, Colo.

Application November 23, 1949, Serial No. 6,227

Term of patent 7 years

(Cl. D57—1)

To all whom it may concern:

Be it known that I, Donald D. Dixon, a citizen of the United States of America, residing at Fort Morgan, Morgan County, and State of Colorado, have invented a new, original, and ornamental Design for a Pin-Up Spectacle Case or Similar Article, of which the following is a specification, reference being had to the accompanying drawing, forming a part thereof.

In said drawing:

Fig. 1 is a rear elevational view of a pin-up spectacle case or similar article showing my new design;

Fig. 2 is a front elevational view of the same;

Fig. 3 is an end elevational view thereof, looking through the right end of the case in Fig. 2; and

Fig. 4 is an enlarged perspective view of the attachment element shown on the rear elevational view in Fig. 1, on an enlarged scale.

I claim:

The ornamental design for a pin-up spectacle case or similar article, substantially as shown.

DONALD D. DIXON.
